UNITED STATES PATENT OFFICE.

WALTER S. TIMMIS, OF BROOKLYN, NEW YORK.

CLUTCH.

SPECIFICATION forming part of Letters Patent No. 760,822, dated May 24, 1904.

Original application filed March 10, 1902, Serial No. 97,504. Divided and this application filed December 9, 1902. Serial No. 134,474. (No model.)

To all whom it may concern:

Be it known that I, WALTER S. TIMMIS, a citizen of the United States, residing at Brooklyn, county of Kings, State of New York, (and having a post-office address at 110 Fifth avenue, borough of Manhattan, city and State of New York,) have invented certain new and useful Improvements in Clutches, of which the following is a full and true description, reference being had to the accompanying drawings, showing one form of my invention and the employment thereof with a pattern-controlled machine—for instance, a machine for producing, assembling, or printing a line of characters or impressions.

My present application is a division of the pending application, Serial No. 97,504, filed March 10, 1902, for machines for producing justified lines. The form of clutch hereinabove described and the controlling connections therefor may be employed for other purposes.

The objects of this invention are, first, to provide a device which may be alternately employed as a clutch and as a brake; second, to provide means for automatically operating the brake; third, to employ an electromagnet for operating the brake and to provide connections for automatically energizing the magnet; fourth, to provide a locking mechanism operating at desired times to hold the clutch in disconnecting position; fifth, to provide means whereby when the clutch has been locked the circuit through the clutch-operating electromagnet will be broken; sixth, to provide means for automatically operating the locking mechanism; seventh, to employ an electromagnet for this purpose and to cut the same out of circuit when the locking mechanism has been moved to locking position, and, eighth, to provide means for holding the locking mechanism in locking position after the magnet has been cut out.

In the practical employment of the machine illustrated in my aforesaid application I have found it advantageous to employ a clutch and to automatically operate the same for the purpose of disconnecting the driven shaft from the main shaft at the conclusion

of each line, whereby the mechanism for producing, assembling, or impressing characters will be at rest during the return of the paper-carriage or other base to commence a new line, and in order that the machine shall not require constant attention I have found it advantageous to provide a locking mechanism which shall, whenever a pattern-strip is exhausted or a "job" is completed, engage the clutch upon its movement to disconnecting position and hold it, thus cutting the machine out of service until again started by an attendant. The clutch-operating means and the lock-operating means should of course be constantly ready for advantageous service, and I prefer to employ electromagnets for controlling these parts. I have found, however, that whenever the clutch is locked, as aforesaid, the magnet which operates the clutch and the magnet which operates the locking mechanism should be cut out of circuit in order to save current and to prevent heating of the magnet-coils, and consequent danger of short-circuiting. This result is accomplished, as shown in the drawings, by providing an automatically - operating circuit-breaker, preferably one controlled by the locking mechanism when at or moving to locking position. In addition I provide means for holding the locking mechanism in locking position after the magnets are cut out of circuit and until an attendant restores the locking mechanism to normal position.

Referring to the accompanying drawings, Figure 1 is a diagram showing the wiring and electrical connections necessary to effect automatic operation and cutting out of the clutch-operating and locking-mechanism-operating devices when applied to a machine for producing, assembling, or impressing lines of characters. Fig. 2 is a plan view of a part of such a machine, showing the pattern-feeding mechanism and the clutch and locking mechanism and their controlling-magnets. Figs. 3, 4, 5, and 6 are views of the clutch and locking mechanism, Fig. 3 showing a longitudinal section of the details of the clutch and driving and driven connections. Figs. 4 and 5 are fragmentary details showing relations of clutch, locking

mechanism, and magnets; and Fig. 6 is a sectional detail showing the clutch disconnected and locked and the contacts of the circuit of the clutch-lock magnet, whereby the circuit of said magnet is broken.

The machine is provided with an automatically-operating clutch for connecting the machine with and disconnecting it from a driving device, such as a pulley and shaft.

10 I prefer to employ a device substantially like that illustrated in the accompanying drawings. This includes a combined clutch and brake and operates to simultaneously disconnect the machine and apply braking pull to the main shaft and to simultaneously connect the machine and remove the brakes.

Referring now to Figs. 3, 4, 5, and 6, I have shown a form of electromagnetically-controlled combined clutch and brake, together with means for automatically locking the device in disconnected and braked position, as hereinafter explained.

D indicates the main shaft, and E the driving-shaft, supported upon a casting H³ of the machine. A driving-pulley H⁴, Figs. 1 and 2, is secured upon such driving-shaft.

H indicates an electromagnet secured to an upright H⁷.

H' indicates a ring-clutch slidably fitted by keyway and key upon the main shaft.

H⁵ indicates a coiled spring fitted around a collar H⁶, which bears against the upright H⁷ and through which the shaft passes. The ends of such spring bear, respectively, against the inner side of the upright and against the sliding ring H'.

H² indicates a fixed ring secured to the extremity of the shaft E. Both H' and H² are provided with interfitting teeth and depressions H⁷, and when the ring H' is advanced by the spring H⁵ it engages and is driven by the driving-ring H², whereby motion is communicated to the main shaft D of the machine.

It will be noticed that the inner edges of the ring H' and the outer edges of the magnet H are correspondingly beveled. When, therefore, the magnet is energized, the attracted ring H', operating against the compression of the spring H⁵, will be brought solidly against the magnet and will be simultaneously disconnected from the driving member H². The pull exerted by the magnet H upon the ring will of course prevent rotation of the latter, and the ring being keyed upon the main shaft D will hold the latter against rotation. From this it will be seen that the arrangement shown simultaneously and by a single device disconnects the machine and applies braking power thereto.

60 Under certain circumstances, as hereinafter explained—as, for instance, when the pattern-strip contains no perforations, as at the end of an article—the machine after having been automatically disconnected is to be maintained in such relation, and I have therefore provided

a lock or catch to accomplish this purpose. The preferred form comprises an electromagnet H⁸, hereinafter designated the "clutch-holder magnet," and which (see Fig. 1) is included by wire J³ in circuit with a circuit-closer carried by the armature J² of the "detector-magnet" J, and which is also included by conductors and by self-governed contacts H¹⁸ and H¹⁷, hereinafter described, in series with the "brake-magnet" H.

The electromagnet H⁸, as shown in Figs. 3, 4, 5, and 6, is provided with an armature H⁹, secured to a vertically-disposed rocking shaft H⁷, upon the upper end of which is fitted a locking-arm H¹⁰, provided at its extremity with a hook H¹¹. The slideable ring H' is provided with an annular groove H¹², shaped to receive the hooked end of the locking-arm H¹⁰. The lower end of the vertical shaft H⁷ is provided with an upper contact-arm H¹⁴, which is fitted to the pin, and a lower contact-arm H¹⁵, which is movable independently of the pin. A spring H¹⁶, connected to both arms, normally tends to hold contacts H¹⁷ and H¹⁸, one carried by each arm, in circuit-closing position. Thus when the clutch-holder magnet H⁸ is energized the attraction of its armature not only throws the arm H¹⁰ to locking position, but also throws forward the arm H¹⁴, and with it by reason of the connecting-spring H¹⁶ the arm H¹⁵, maintaining the circuit through the magnets H⁸ and H constantly closed. This would be undesirable from the fact that if the machine is left disconnected and locked for a long time the magnets H and H⁸ would become overheated and might be burned out or short-circuited.

I have therefore provided means for separating the contacts H¹⁷ and H¹⁸ upon the arms H¹⁴ and H¹⁵, when the clutch is securely locked, and other means whereby the locked parts are mechanically held in that relation. Extending upwardly from the base of the machine is a trip-pin H¹⁹, over the top of which the arm H¹⁴ moves without interference, but which pin is in the path of movement of the arm H¹⁵. The outer end of arm H¹⁴ is slotted or forked, and a pin H²⁰, carried by the short arm of a lever H²¹, is adapted to move the said arm. H²² is a lever for manually throwing the lever, and H²³ is a spring connected to the pin H²⁰ and to the machine and operative to hold the lever in either the locking or unlocking position. H²⁴ is a stop against which the lever rests in the first-named position.

The normal position of the parts is shown in Figs. 3 and 4, wherein the clutch engages the driving-gear, and the magnet H⁸ being inoperative the locking-arm is drawn away from ring H'. It will be seen that the lever H²¹ is thrown to the extreme left of its pivot (the screw H²⁵) and that the arm H¹⁴, moved by the pin H²⁰, is thrown outwardly and by reason of the engagement of contacts H¹⁷ and H¹⁸ has also thrown the arm H¹⁵ outwardly. When,

however, the clutch-holder magnet H^8 is energized, the shaft H^{16} is turned and the arm H^{14} draws the arm H^{15} forward until stopped by the trip-pin H^{19} and meanwhile has also drawn the short arm of the lever H^{21} until the line of pull of the spring H^{23} is to the rear of the center of the pivot-screw H^{25} , whereupon the said spring completes the locking movement of the parts and the separation of the contacts H^{17} and H^{18} . In this position the parts will remain until manually restored by the operation of the lever H^{21} .

It will be noticed that the separation of the contacts H^{18} and H^{17} breaks the circuit through both magnets H and H^8 , and this prevents the heating of the same and the liability to short-circuiting through either or both of the magnets. It will also be noticed that when the magnet H^8 is cut out of circuit the hook H^{11} will not disengage the groove H^{12} of the clutch, but will be securely held therein by the tension of the spring H^{23} , which exerts a pull on the lever H^{21} .

To unlock the disconnected clutch and to permit it to return to connecting position, it will be necessary in the illustrated form of my invention to throw the lever H^{21} to the position shown in Fig. 3, whereupon the spring H^{23} exerts a downward pull on the lever and 30 brings the contacts H^{18} and H^{17} into engagement with each other.

The form of clutch invented by me is especially advantageous in connection with a machine controlled by a perforated pattern-strip for printing, producing, or assembling lines of characters, but may be employed with any other kind of pattern-controlled machine. Machines for printing, producing, or assembling lines of characters are preferably controlled by a pattern—usually a pattern-strip having openings representing the characters, openings representing interword-spaces, openings controlling the width of the interword-spaces, and openings representing the end of 45 a line.

In the practical operation of a machine of the character described the strip or other pattern is moved step by step and in such relation to character-selecting or space-making mechanisms as to cause these mechanisms to select in the predetermined order the desired characters and to space the words by complete or fractions of units, so as to exactly fill the predetermined length of line, and the 55 movement of the pattern causes the operation upon presentation of an opening or other representation of the end of a line of a carriage or base to commence a new line of characters or impressions and also disconnects the 60 machine until the said movement of the carriage or base is completed. The clutch for effecting disconnection of the machine is to be operated automatically upon presentation of a "line-strip" opening, and the preferred 65 connections for effecting this are shown in

Figs. 1 and 2 of the accompanying drawings. I have also found it to be advantageous in the practical operation of machines of the character described to provide means whereby the machine will stop at the conclusion of the perforations representing an article or job and will remain inoperative as long as desired. This not only saves wear of the machine and prevents waste of power, but one attendant may care for several machines, and the stopping of any machine will be notice to him that the pattern must be renewed or the article or job taken from the machine. To effect this automatic stoppage of the machine, I have preferred to employ means set into operation only when the pattern is advanced to a portion which lacks perforations representing characters, spaces, or the end of a line. I prefer to employ electrical connections for this purpose and have shown one form in Fig. 1 of the accompanying drawings.

Referring especially to Fig. 2 of the drawings, which indicates a top view of the related parts of a machine necessary to explain the operation of my present invention, the driven shaft D is provided with a cam A^{24} , for operating the circuit-closer frame and pattern-feeding mechanism; a cam D' , acting to drive in one direction a lever which longitudinally moves a character-bearing body; a cam D^2 , 95 acting to revolve the shaft upon which the type-cylinder is fitted; a cam D^3 , for moving a lever for operating the carriage-driving mechanism; a cam D^4 , for moving an inking mechanism; a cam D^5 , for locking the character-bearing body in selected position; a cam D^6 , for oscillating a paper-holding frame on the traveling carriage in order to move the paper to impression-taking position, and a cam J^{95} , operating upon a lever-arm of a detector-magnet, which controls the circuit through the clutch-locking magnet. The driven shaft also carries and drives a rotary switch comprising a main contact L' and branching plates L^2 and L^3 , situated at opposite sides of L' .

The relation, connection, and operation of the cams and other specified parts will be found described in detail in my aforesaid application, Serial No. 97,504.

In Fig. 2 I have shown my improved clutch 115 as being combined with the machine for printing justified lines described and claimed in said application. Said machine is provided with uprights A^2 A^2 and with a pair of feeding-rolls (one of which is indicated at A^{10}) for 120 drawing a perforated pattern underneath a contact-frame A^{28} , which carries the pins—such as A^{35} A^{41} , Fig. 1. The frame is raised and lowered by means of an arm A^{26} , secured to a rocking shaft A^{21} and to the outer end of which 125 is secured an arm A^{20} , the free end of which carries a pawl engaging a ratchet for driving the feeding-rolls. The rocking of the shaft A^{21} is effected by means of a roller D on the forward end of an arm A^{22} , a cam A^{24} (by con- 130

tact with the roller) moving the arm in one direction, while the spring A^{25} returns said arm. The contact-pins of the frame A^{28} , which pass through the perforations of the pattern, 5 close the circuits of magnets which control the positioning of a type-cylinder M^3 with relation to paper carried by a paper-carrying traveling carriage X . The type-cylinder referred to is returned both longitudinally and 10 rotationally to a zero position by levers M and M^{10} and by connections described in detail in my said application Serial No. 97,504, these levers being driven in one direction by cams D' and D^2 and in the other direction by cams M^2 15 and M^{11} . Rotary switch connections $L' L^2 L^3$ are provided for first closing the circuits through the selected magnet or magnets aforesaid and for then closing a circuit through an impression-taking magnet B^5 , moving the hammer-arm T^2 , all as described and claimed in detail in my aforesaid application.

Referring to Fig. 1, it may be explained that the contacts C' and A^{35} to A^{41} , inclusive, are fixed, and the coöperating contacts C and 25 A^{35} to A^{41} , inclusive, are carried by a movable frame A^{28} of Fig. 2. This last-named frame is controlled by the cam A^{24} , and a pattern-feeding mechanism, composed partly of a lever A^{20} and feed-roller A^{10} , operates alternately with the frame, whereby the pattern is fed when the upper contacts C and A^{35} to 30 A^{41} are raised, and when the pattern is at rest the frame is lowered, causing one or more of the upper contacts to pass through openings 35 in the pattern, and thereby bringing one or more of the upper contacts into touch with one or more of the lower contacts.

The contacts A^{35} to A^{41} , inclusive, are connected to conductors which lead to the cores 40 of magnets $A^{76} A^{77} A^{78} A^{79} A^{80}$ and $a' a^2$, and these magnets (which are directly included by conductors Y , T^{19} , and b^8 with generator Z) control, as fully explained in my aforesaid application, means for arresting a character-bearing body at a desired position and 45 for controlling the operations of a paper-carriage or other base, and the contact C' is connected to a conductor c , which leads (through a line-trip magnet C^2 , carriage-contact C' , and conductor C') to the coil of the clutch-operating magnet H and then by wire 50 b^8 to generator Z . The contacts A^{35} to A^{41} pass through openings in the pattern representing characters, and the contact C passes only 55 through openings, hereinbefore designated "line-trip" openings, at the end of a line. Obviously whenever the end of a line is reached some part of the machine must be moved, shifted, or restored for the making of 60 a new line of characters or impressions, and the operations of the character producing, assembling, or impression means must be stopped during such moving, shifting, or restoration. This is done in the apparatus illustrated by me by causing the magnet H to dis-

connect the clutch and draw the ring H' tightly to the magnet-shell, causing the magnet to act as a brake. When the carriage or base has been moved, shifted, or restored, it may automatically break the circuit through the 70 magnet—as, for instance, by separating contacts, such as $C^3 C^4$ of Fig. 1, included in the circuit from the line-trip contact C' to the magnet H .

As shown in Fig. 1, the machine may employ a magnet J , known as a "detective" and located in the line which leads to the movable contact-frame A^{28} aforesaid. Thus whenever one or more of the branch circuits is or are closed by the passing of the contacts A^{35} to 75 A^{41} and C through the openings of the pattern-strip current will pass through the core of magnet J , and the armature J^2 thereof will be attracted, so as to separate two contacts $J^{98} J^{99}$; but whenever the pattern mechanism 80 presents a portion of the strip which has no holes, as at the end of an article or completion of a "job," then the branch circuits will not be closed by the movable frame, and the magnet J will not be energized. When this 85 happens, the armature J^2 will fall and the contacts J^{98} and J^{99} will engage, thus closing a circuit through the coil of the magnet H^8 , through the contacts H^{17} and H^{18} , and through the magnet H . The armature H^9 of the locking-magnet H^8 will thereupon be attracted 90 and will move the hook H^{11} to position to engage the groove H^{12} of the clutch-ring as soon as the latter moves sufficiently. When 95 the hook enters the groove, as shown in Figs. 100 3 and 6, the contacts $H^{17} H^{18}$ will separate and the circuit will be broken, and, as explained, the spring H^{23} will maintain the parts in such position until manually restored. It will readily be seen, therefore, that the clutch will be 105 disconnected at the end of each line of characters or impressions and that at the conclusion of an article the clutch will also be locked in disconnecting position.

I claim—

1. In a pattern-controlled machine, the combination of a driven shaft, a clutch carried thereby, automatically-operating means for controlling the clutch, and means for locking the clutch as desired, substantially as described.

2. In a pattern-controlled machine, the combination of a driven shaft, a clutch carried thereby, means for controlling the clutch, and automatically-operating means for locking the clutch as desired, substantially as described.

3. In a pattern-controlled machine, a driven shaft, a main shaft, a combined clutch and brake, and automatically-operating means for controlling the combined device, whereby it 115 may be employed alternately as a clutch for connecting the shafts and as a brake for the driven shaft, substantially as described.

4. In a pattern-controlled machine, a driven shaft, a main shaft, a combined clutch and 120

brake, and means for controlling the combined device, whereby it may be employed alternately as a clutch for connecting the shafts, and as a brake for the driven shaft, substantially as described.

5. In a machine of the character described, a driven shaft, a main shaft, a combined clutch and brake, means for controlling the combined device, whereby it may be employed alternately as a clutch for connecting the shafts and as a brake for the driven shaft, and means for locking the combined device in braking position, substantially as described.

6. In a machine of the character described, 15 a driven shaft, a main shaft, a clutch for connecting said shafts, means for operating the clutch, and means for locking the clutch in disconnected position when desired, substantially as described.

20 7. In a machine of the character described, a driven shaft, a main shaft, a clutch for connecting said shafts, means for operating said clutch, and automatically-operating means for locking the clutch in disconnected position 25 when desired, substantially as described.

8. In a machine of the character described, a driven shaft, a main shaft, a clutch for connecting said shafts, automatically-operating means for controlling said clutch, and automatically-operating means for locking the clutch in disconnected position when desired, substantially as described.

35 9. In a machine of the character described, a pattern-feeding mechanism, a driven shaft, a main shaft, a clutch for connecting the shafts, an electromagnet controlling said clutch, means under control of the pattern-feeding mechanism for closing the circuit through the electromagnet, and a locking mechanism, controlled by the pattern-feeding mechanism, for holding the clutch in disconnected position as desired, substantially as described.

40 10. In a machine of the character described, a pattern-feeding mechanism, a driven shaft, a main shaft, a clutch for connecting said shafts, connections between the pattern-feeding mechanism and the clutch for automatically operating the latter, and a locking mechanism, controlled by the pattern-feeding mechanism, for holding the clutch in disconnected position as desired, substantially as described.

45 11. In a machine of the character described, a pattern-feeding mechanism, a driven shaft, a main shaft, a clutch for connecting said shafts, connections between the pattern-feeding mechanism and the clutch for automatically operating the latter, a locking mechanism for holding the clutch in disconnected position, an electromagnet controlling the locking mechanism, and means, under control of the pattern-feeding mechanism, for closing the circuit of the electromagnet, substantially as described.

50 65 12. In a machine of the character described,

a pattern-feeding mechanism, a driven shaft, a clutch for connecting said shafts, an electromagnet controlling the clutch, means, under control of the pattern-feeding mechanism, for closing the circuit through the electromagnet, 70 a locking mechanism for holding the clutch in disconnected position, an electromagnet controlling the locking mechanism, and means, under control of the pattern-feeding mechanism, for closing the circuit of the electromagnet, 75 substantially as described.

13. In a machine of the character described, a driven shaft, a main shaft, a clutch for connecting said shafts, an electromagnet controlling the clutch, automatically-operating 80 means for closing the circuit of the electromagnet, a locking mechanism for holding the clutch in disconnected position, an electromagnet controlling the locking mechanism, and automatically-operating means for closing 85 the circuit of the last-named electromagnet, substantially as described.

14. In a machine of the character described, a driven shaft, a main shaft, a clutch for connecting said shafts, means for operating said 90 clutch, a locking mechanism for holding the clutch in disconnected position, an electromagnet controlling the locking mechanism, and automatically-operating means for closing 95 the circuit of the electromagnet, substantially as described.

15. In a machine of the character described, a driven shaft, a main shaft, a clutch for connecting said shafts, means for operating said clutch, a locking mechanism for holding the 100 clutch in disconnected position, an electromagnet for controlling the locking mechanism, and a contact operated by the locking mechanism to render the magnet ineffective when the clutch is locked, substantially as described. 105

16. In a machine of the character described, a driven shaft, a main shaft, a clutch for connecting said shafts, means for operating said clutch, a locking mechanism for holding the 110 clutch in disconnected position, an electromagnet for controlling the locking mechanism, a circuit-breaker operated by the locking mechanism and breaking the circuit through the magnet, and a spring for holding the locking mechanism in locking position, substantially 115 as described.

17. In a machine of the character described, a driven shaft, a main shaft, a clutch for connecting said shafts, an electromagnet for operating said clutch, a locking mechanism for holding the clutch in disconnected position, and a contact operated by the locking mechanism to render the magnet ineffective when the clutch is locked, substantially as described. 125

18. In a machine of the character described, a driven shaft, a main shaft, a clutch, an electromagnet for operating said clutch, a locking mechanism for holding the clutch in disconnected position, a circuit-breaker operated by 130

- the locking mechanism and breaking the circuit through the magnet, and a spring for holding the locking mechanism in locking position, substantially as described.
- 5 19. In a machine of the character described, a driven shaft, a main shaft, a clutch, an electromagnet for operating said clutch, a locking mechanism for holding the clutch in disconnected position, an electromagnet for controlling 10 the locking mechanism, a circuit-breaker operated by the locking mechanism and breaking the circuit through both electromagnets, and a spring for holding the locking mechanism in position, substantially as described.
- 15 20. In a machine of the character described, a driven shaft, a main shaft, a clutch, an electromagnet for operating said clutch, a locking mechanism for holding said clutch in disconnected position, an electromagnet for controlling 20 the locking mechanism, and automatically-operating means for breaking the circuit through both magnets when the locking mechanism is in locking position, substantially as described.
- 25 21. In a machine of the character described, a driven shaft, a main shaft, a clutch, means for operating the clutch, a locking mechanism for holding said clutch in disconnected position, and automatically-operating means for 30 holding the locking mechanism in locking position, substantially as described.
- 35 22. In a machine of the character described, a driven shaft, a main shaft, a clutch slidably mounted upon the driven shaft and provided with an annular rib, an electromagnet for controlling 40 the movement of the clutch to disconnecting position, a locking-hook for engaging the groove when the clutch is moved as aforesaid, and means for operating the locking-hook, substantially as described.
- 45 23. In a machine of the character described, a driven shaft, a main shaft, a clutch slidably mounted upon the driven shaft, and provided with an annular rib, an electromagnet for controlling the movement of the clutch to disconnecting position, a locking-hook for engaging the groove when the clutch is moved as aforesaid, and an electromagnet for operating the locking-hook, substantially as described.
- 50 24. In a machine of the character described, a driven shaft, a main shaft, a clutch slidably mounted upon the driven shaft and provided with an annular rib, means for controlling the movement of the clutch to disconnecting 55 position, a locking -hook for engaging the groove when the clutch is moved as aforesaid, and automatically-operating means for operating the locking-hook, substantially as described.
- 60 25. In a machine of the character described, a driven shaft, a clutch for connecting and disconnecting said shafts, and provided with an annular rib, an electromagnet for controlling the movement of the clutch to disconnecting 65 position, a locking -hook for engaging the
- groove when the clutch is moved as aforesaid, an electromagnet for operating the locking-hook as desired, a circuit-breaker operated in conjunction with the locking-hook and breaking the circuit of the two electromagnets 70 aforesaid, and means for holding the hook in locking position, substantially as described.
26. In a machine of the character described, a driven shaft, a main shaft, a clutch for connecting and disconnecting said shafts and provided with an annular rib, an electromagnet for controlling the movement of the clutch to disconnecting position, automatically-operating circuit-closing means for said magnet, a locking-hook for engaging the groove when 80 the clutch is moved as aforesaid, an electromagnet for operating the hook as aforesaid, automatically-operating circuit-closing means for the last-named magnet, a circuit-breaker operated in conjunction with the locking-hook 85 and breaking the circuit of the two electromagnets aforesaid, and a spring for holding the hook in locking position, substantially as described.
27. The combination, with a machine, of a driven shaft, a combined clutch and brake carried thereby, and means operated by said machine for controlling the combined device, whereby it may be employed alternately as a clutch and as a brake for the driven shaft, 95 substantially as described.
28. The combination, with a machine, of a driven shaft, a combined clutch and brake carried thereby, and automatically-operating means for controlling the combined device, 100 whereby it may be employed alternately as a clutch and as a brake for the driven shaft, substantially as described.
29. The combination, with a machine, of a driven shaft, a combined clutch and brake carried thereby, an electromagnet for controlling the combined device, and means operated by the machine for making and breaking the circuit of said electromagnet, substantially as described.
30. The combination, with a machine, of a driven shaft, a combined clutch and brake carried thereby, an electromagnet for controlling the combined device, and automatically-operating means for making and breaking the circuit of said electromagnet, substantially as described.
31. The combination, with a machine, of a driving - shaft, a driven shaft, a combined clutch and brake, and means operated by said machine for controlling the combined device, whereby it may be employed alternately as a clutch for connecting the driving and driven shafts and as a brake for the driven shaft, substantially as described.
